ELECTRIC STARTER FOR INTERNAL
COMBUSTION ENGINES

Joseph Bethenod, Paris, France, assignor to Societe De Paris Et Du Rhone, Lyon, France, a corporation of France

Application January 2, 1931, Serial No. 506,075
In France February 12, 1930

3 Claims. (Cl. 74—6)

It has been proposed, in particular for the starting of internal combustion engines, to employ an electric motor operatively connected to the shaft of the engine to be started by a transmission mechanism which ensures that once the starting is effected an automatic disengagement of the said transmission mechanism from the engine shaft is effected. It is known to use in particular in order to produce this effect, transmission mechanism including elastic means which are associated, on the one hand with the shaft of the electric starting motor, and on the other hand, with a driving member arranged concentrically to said shaft.

The object of the invention is to provide improvements of said mechanism presenting remarkable advantages as regards the safety, durability, simplicity and economy. The invention relates more specifically to a form in which the elastic means employed consists of a helical spring having serially disposed windings, affording flexible operation, efficient functioning and reduced size of construction. Figures 1 and 2 of the accompanying drawing disclose diagrammatically the construction of an apparatus for carrying the invention into effect.

Referring to the drawing, a shaft 1 of an electric starting motor (not shown) or a shaft of a reducing gear driven therefrom has a pinion 2 rotatably and slidably mounted thereon and arranged under the control of a fork (not shown) which extends into a groove 3 formed in a boss on the pinion. A flat spirally wound flexible strip 6 of a material such as steel, fibre or the like is arranged within a recess formed in the pinion at 4 so as to surround the shaft 1 with which it engages with a relatively slight degree of friction. One end 7 of the strip 6 is fixed to the pinion while the other end rests freely upon the shaft 1.

When it is desired to effect the starting of the internal combustion engine, the unit 2, 3, 6 is caused to slide along the shaft 1, in such manner that the pinion 2 meshes with a toothed crown wheel 5 keyed to the shaft of the engine, the electric starting motor being energized at the same time. The direction of coiling of the spring 6 is so arranged with respect to the direction of rotation of the shaft 1, that as soon as the pinion 2 meshes with the crown wheel 5, an energetic automatic tightening of the said spring upon the shaft 1 is effected so that the electric motor drives the pinion 2 and crown wheel 5 and the internal combustion

engine is started. As soon as the engine rotates, under its own power, the clamping effect of the spring 6 upon the shaft 1 becomes reduced and finally when the crown wheel 5 commences to drive the pinion 2, the spring 6 forms a free wheel device which avoids any damage to the transmission before the pinion 2 has been disengaged by the manipulation of the fork controlling the said pinion.

The section and length of the spring 6 are selected according to circumstances whilst means such as a brake may be provided to increase, either permanently or temporarily, the friction of the free end of the spring with the shaft 1. Finally, the operative and return movements of the pinion 2 may be brought about by any suitable means other than the fork system described.

It will be also understood that this variation of the invention comprises various methods of execution within the scope of the invention. For example, the strip 6 may be mounted within the casing 4 secured to or integral with the pinion 2 which then contacts directly with the shaft 1.

I claim:

1. A clutch comprising a smooth and uniform driving shaft, a driven element upon said shaft, and an elastic means upon said shaft aligned with said driven element and solely enveloping said shaft, which elastic means has one end free and the other end rigidly attached to the driven element so that said elastic means is rotatable in one direction with said driven element upon said shaft, while in the other direction the elastic means frictionally grips the shaft and causes both said elastic means and the driven element to rotate positively with the shaft, and means for axially sliding said driven element together with said elastic means along the shaft for the purpose of coupling the driven element with a motion transmission system.

2. A spring clutch comprising a smooth and uniform driving shaft, a driven element upon said shaft, and a helical spring upon said shaft aligned with said driven element and solely enveloping the shaft, which helical spring has one end free and the end adjacent the driven element rigidly attached thereto so that the spring is rotatable in one direction with said driven element upon the shaft, while in the other direction said spring frictionally grips the shaft and causes both the spring and the driven element to rotate positively with said shaft, and means for axially sliding said driven element together with said helical spring along the shaft in order to couple the

driven element with a motion transmission system.
3. A spring clutch comprising a smooth and uniform driving shaft, a driven element upon said shaft, and a flat spiral spring upon said shaft
5 aligned with said driven element and solely enveloping the shaft, which flat spiral spring has one end free and the other end rigidly attached to said driven element so that the spring is rotatable in one direction with said driven element

upon the shaft, while in the other direction said spring frictionally grips the shaft and causes both the spring and the driven element to rotate positively with said shaft, and means for axially sliding said driven element together with said flat spiral spring along the shaft in order to couple said driven element with a motion transmission system.
